UNITED STATES PATENT OFFICE.

LESLIE M. PARKER, OF EVANSTON, ILLINOIS.

FASTENER.

Application filed April 18, 1921. Serial No. 462,176.

To all whom it may concern:

Be it known that I, LESLIE M. PARKER, a citizen of the United States, residing at Evanston, in the county of Cook and State 5 of Illinois, have invented a certain new and useful Improvement in Fasteners, of which the following is a specification.

This invention relates to means for securing a plurality of sheets together. It 10 is especially adapted for use where it is desired to secure together a number of sheets of perforated paper. It has for one object, to provide a fastener that can be quickly put in use and quickly released. 15 Another object is to provide a fastener which can be used to secure together a widely varying number of sheets, without any change in form or other readjustment. Other objects will appear from time to 20 time throughout the specification and claims.

The invention is illustrated more or less diagrammatically in the accompanying drawings, wherein—

25 Fig. 1 is a plan view of the fastener in place, with parts shown in dotted lines;

Fig. 2. is a vertical section on line 2—2 of Fig. 1;

30 Fig. 3 is a view similar to Fig. 2 showing the parts in position for use;

Fig. 4 is a view similar to Fig. 3 with the parts turned through an angle of 90°;

Fig. 5 is a horizontal section on line 5—5 of Fig. 3;

35 Fig. 6 is a vertical section of a modified form;

Fig. 7 is a vertical section of a further modification;

Fig. 8 is a view similar to Fig. 4 showing 40 the modified form of Fig. 7;

Figs. 9 and 10 show a further modification;

Fig. 11 is a further modification.

Like parts are designated by like characters throughout.

A is a pile of sheets of paper, perforated at A', Communicating with the perforation A' is a slot A², which may be omitted.

B is the outer member of the fastener.

50 It has the two upwardly extending arms B' B', terminating in the hooks B², B². These hooks are shown as having rounded ends, but the shape of the ends might be varied. B³ is a lateral tongue from the

55 member B. It is adapted to project beyond the edge of the material with which it is

used and to be bent about it, as shown in the drawings, to prevent rotation of the member with relation to the material which it is holding. 60

C is the inner member. In the form shown in Figs. 3 and 4 it is substantially circular in section; although this is not necessary. It is provided with the flat head C' which has in its under side the point C² 65 adapted to engage or penetrate the material which it is holding, in the manner shown in Fig. 2. The shank of the member C has the two oppositely arranged smooth surfaces C³, C³ and the two oppositely arranged notched surfaces C⁴ C⁴. 70

Instead of the point C² any ridge or formation adapted to engage the upper surface of A and prevent rotation of the part C might be substituted. 75

In the form shown in Fig. 6 the under side of the part G' is smooth and the tongue C⁵ is provided. This tongue is attached to G' and is adapted to be bent, as shown in Fig. 6, to prevent rotation of the member G. 80

In the form shown in Figs. 7 and 8 a different form of the upper member is used. It consists of the part D, having the downwardly extending notched arms D' D', 85 adapted to be engaged by the hooks F² F². The tongue D² is provided and is adapted to be bent downwardly about the block of material to prevent rotation of the part D.

In the form shown in Figures 3 and 4 90 the member B is made wider than the distance between the arms B' B', so as to overlie and extend beyond the edges of the hole into which the arms are inserted. In the form shown in Figures 7 and 8 this is not 95 the case. Thus the member F has no lateral projections and it and the member F³ are substantially of the same width as the gap between the two upwardly extending members F' F'. Either form may be used, but 100 each has features which recommend it for certain uses. The arms B' B' contact the inside of the perforations of the sheets adjacent the hooks B² B² and they are thus additionally supported. This feature, while 105 not necessary, is one which makes to strengthen the hold of the parts on each other and to make accidental displacement less likely.

In the form shown in Figs. 9 and 10 a 110 tubular section H is used as the receiving member in place of the preferred form of re-

ceiving member. This tubular section has in it towards its top the oppositely placed notches H' H' and is intended to be used in connection with the inner member C. Its use is the same as that of the member previously described. In Fig. 11 the tubular member is shown as being notched along two rows of oppositely placed notches H^2 H^2 . This member may be used with the 10 inner member C as shown in Fig. 3 or with the modified form I of that member as shown in Fig. 11, wherein the member is not notched throughout its length, but is provided only at its bottom with the oppositely placed hooks I^6 I^6 .

The use and operation of my invention are as follows:

Where, for example, sheets of paper are to be fastened together, they are arranged as shown. The lower member is then inserted in the hole with the tongue pointing to the left; and the tongue is then bent up about the body of the paper. The upper member is then inserted, with the point C^2 to the right. The member is pushed down till the head contacts the upper surface of the pile of paper. When this point is reached, the point C^2 will have engaged the paper so as to prevent rotation and the hooks on the 25 arms of the lower member will have engaged the notches in the sides of the upper member so to prevent withdrawal of that member. The papers are thus firmly held together as shown in Figs. 1 and 2.

When it is desired to separate the members and free the sheets of paper, the tongue of the lower member is depressed and that member is rotated through an angle of 90° , and the parts are then free to be withdrawn, 30 as the hooks in the lower member no longer engage the notches in the upper member.

In the form shown in Fig. 6 the tongue of the upper member is bent down in the same manner that the tongue of the lower member is bent up. To release the hold of this 45 form, either of the members may be rotated.

The operation of the form shown in Figs. 7 and 8 is the same as that of the form shown in Fig. 6. The lower ends of the arms D' D' may or may not be joined.

Although I have shown an operative form of my invention, still it will be obvious that many changes both in form, shape and arrangement of parts may be made without departing from the spirit of my invention, and I wish therefore that my showing be taken as in a sense diagrammatic.

I claim:

1. As a new article of manufacture a 60 fastening device comprising two interlocking parts, one adapted to surround and grip the other, said parts held against relative longitudinal movement when in one relative position and free to have relative longitudinal movement when rotated from that position,

and means for preventing accidental rotational movement of said parts, said surrounding part including two spring gripping members.

2. As a new article of manufacture, a 70 fastening device for securing together a plurality of sheets of perforated material, comprising two interlocking members adapted to lie within said perforations, one adapted to surround and grip the other, said surrounding member including two upwardly extending hook arms, said surrounded member including a shank having two oppositely placed smooth surfaces and two oppositely placed notched surfaces, said notched surfaces positioned between said smooth surfaces and adapted to be engaged by said hook arms. 75

3. As a new article of manufacture, a 80 fastening device for securing together a plurality of sheets of perforated material, comprising two interlocking members adapted to lie within said perforations, one adapted to surround and grip the other, said surrounding member including two upwardly extending hook arms, said surrounded member including a shank having two oppositely placed smooth surfaces and two oppositely placed notched surfaces, said notched surfaces positioned between said smooth surfaces and adapted to be engaged by said hook arms, and means for preventing accidental relative rotation of said parts. 90

4. As a new article of manufacture a 100 fastening device for securing together a plurality of sheets of perforated material, comprising two interlocking members adapted to lie within said perforations, one adapted to surround and grip the other, said surrounding member including two upwardly extending hook arms, said surrounded member including a shank having two oppositely placed smooth surfaces and two oppositely placed notched surfaces, said notched surfaces positioned between said smooth surfaces and adapted to be engaged by said hook arms, and means for preventing accidental relative rotation of said parts, said means comprising members upon each of 105 said parts adapted to engage said sheets of material. 110

5. As a new article of manufacture, a fastening device for securing together a plurality of sheets of perforated material, comprising two interlocking members adapted to lie within said perforations, one adapted to surround and grip the other, said surrounding member including upwardly extending hook arms, said surrounded member including a shank having oppositely placed smooth surfaces and two oppositely placed notched surfaces, said notched surfaces positioned between said smooth surfaces and adapted to be engaged by said hook arms, and means for preventing accidental 120 relative rotation of said parts, 125

5 tive rotation of said parts, comprising a flexible tongue on one of said members adapted to engage said sheets of material to prevent rotation of the member and a projection on the other of said members adapted to engage said material.

6. As a new article of manufacture, a fastening device for securing together a plurality of sheets of perforated material comprising 10 two interlocking members adapted to lie within said perforations, one adapted to surround and grip the other, said surrounding member including two upwardly extending hook arms, said surrounded member including a shank having two oppositely placed smooth surfaces and two oppositely placed notched surfaces, said notched surfaces positioned between said smooth surfaces and adapted to be engaged by said hook arms, said interlocking members held 15 against relative outward longitudinal movement when said notched portions are engaged by said hook members, and free to have relative outward longitudinal movement when said smooth portions are in opposition to said hook members.

7. As a new article of manufacture a fastening device for securing together a plurality of sheets of perforated material comprising 20 two interlocking members adapted to lie between said perforations, one adapted to surround and grip the other, said surrounding member including two upwardly extending hook arms, said surrounded member including a shank having two oppositely placed smooth surfaces and two oppositely placed notched surfaces, said notched surfaces positioned between said smooth surfaces and adapted to be engaged by said hook arms, said interlocking members held 25 against relative outward longitudinal movement when said notched portions are engaged by said hook members, and free to have relative outward longitudinal movement when said smooth portions are in opposition to said hook members, said interlocking members free at all times to have relative inward longitudinal movement.

8. As a new article of manufacture a fastening device adapted to secure together a plurality of perforated sheets of material, said device comprising two interlocking members, one adapted to surround and grip the other, said surrounding member comprising 30 two upwardly extending hook arms, said surrounded member comprising a shank and two oppositely placed smooth surfaces and two oppositely placed notched surfaces, said notched surfaces positioned between said smooth surfaces, one of said members provided with a laterally extended member adapted to bend about an edge of said sheets, the other member provided with means for engaging the exposed surface of 35 one of said sheets.

9. As a new article of manufacture a fastening device adapted to secure together a plurality of perforated sheets of material, said device comprising two interlocking members, one adapted to surround and grip 40 the other, said surrounding member comprising two upwardly extending spring hook arms, said surrounded member comprising a shank and two oppositely placed smooth surfaces and two oppositely placed notched surfaces, said notched surfaces positioned between said smooth surfaces, one of said members provided with a laterally extended member adapted to bend about an edge of said sheets, the other member provided with means for engaging the exposed surface of one of said sheets.

10. A fastener adapted to secure together a plurality of perforated pieces, said fastener comprising a plurality of members 45 adapted to be inserted in a perforation of said pieces, said members adapted when in one relative rotational position to engage with each other and when so engaged to be held against outward movement, said members free for outward movement when rotated from such relative position, said members being adapted 50 to be held against outward movement when rotated from such relative position, said members adapted to be held against operative disengagement from each other by the interior of said perforation.

11. A fastener adapted to secure together a plurality of perforated pieces, said fastener comprising a plurality of members adapted to be inserted in a perforation of said pieces, said members adapted when in one relative rotational position to engage with each other and when so engaged to be held against outward movement, said members free for outward movement when rotated from such relative position, said members being adapted 55 to be held against outward movement when rotated from such relative position, said members adapted to be held against operative disengagement from each other by the interior of said perforation, and means for preventing accidental rotation of said members.

12. A fastener adapted to secure together a plurality of perforated pieces, said fastener comprising a pair of members adapted to be inserted in a perforation of said pieces, said members adapted when in one relative rotational position to engage with each other 60 and when so engaged to be held against outward movement, said members free for outward movement when rotated from such relative position, said members normally free for relative lateral movement and being adapted to be held against operative disengagement from each other by the interior of said perforation.

13. A fastener adapted to secure together a plurality of perforated pieces, said fastener comprising a pair of members adapted to be inserted in a perforation of said pieces, said members adapted when in one relative rotational position to engage with each other and when so engaged to be held against out- 65 70 75 80 85 90 95 100 105 110 115 120 125 130

ward movement, said members free for outward movement when rotated from such relative position, said members normally free for relative lateral movement and being adapted to be held against operative disengagement from each other by the interior of said perforation, and means for preventing accidental rotation of said members.

14. The combination of a plurality of 10 perforated sheets of material with a fastening device adapted to hold them together, said device comprising two interlocking parts, one surrounding and gripping the other, said parts held against relative longitudinal outward movement when in one 15 position and free to have relative longitudinal movement when rotated with relation to each other, and means for preventing accidental rotational movement of the interlocking 20 parts, said means comprising members on each of said parts adapted to engage the sheets of material.

15. The combination of a plurality of 25 perforated sheets of material with a fastening device adapted to hold them together, said device comprising two interlocking parts, one surrounding and gripping the

other, said parts held against relative longitudinal outward movement when in one 30 position and free to have relative longitudinal movement when rotated with relation to each other, and means for preventing accidental rotational movement of the interlocking parts, said means comprising a flexible tongue on the surrounding part and a material-engaging projection on the penetrating part. 35

16. A fastener adapted to secure together a plurality of perforated pieces, said fastener comprising a plurality of members 40 adapted to be inserted in a perforation of said pieces, said members adapted when in one relative rotational position to engage with each other and when so engaged to be held against outward movement, said members free for outward movement when rotated from such relative position, said members being adapted to be held against operative lateral disengagement from each other by the interior of said perforation. 45

Signed at Chicago, county of Cook and State of Illinois, this 16th day of April 1921.

LESLIE M. PARKER.
